FASTENING FOR ATTACHE AND SUIT
CASES AND THE LIKECharles William Cheney, Soho, Birmingham,
EnglandApplication February 24, 1937, Serial No. 127,422
In Great Britain February 26, 1936

4 Claims. (Cl. 70—67)

The invention relates to fastenings for attaché and suit cases and the like of the kind comprising two main members, the one a hasp usually fixed to the hinged lid of the case, and the other a lock or latch, hereinafter referred to as a "lock", usually fixed to the body of the case.

The invention provides a construction of such fastenings whereby hand-release of the hasp from the catches of the lock also starts positive disengagement of the hasp from said lock, so that the lid of the case is partially opened.

The invention also provides a construction of such fastenings whereby on putting the hasp into engagement with the lock, as on closing the lid, the lock catches are positively moved by the hasp into engagement with itself, the complete engagement being afterwards effected by a spring applied to the lock.

The lock catches are pivoted ones, and sometimes a pair is used, and sometimes a single one, said catches being withdrawn to release and eject the hasp either by a revoluble movement of a hand-operated member of the lock or by a sliding movement of a hand-operated member.

The drawings forming part hereof illustrate the invention in five forms differing only in constructional details, all having the same essential features in combination.

Fig. 1 is a section with the hasp and lock in engagement.

Fig. 2 is a back view of Fig. 1 with the back plate of the lock removed.

Fig. 3 is a front view of the hasp Figs. 1 and 2.

Fig. 4 is a front view of the lock Figs. 1 and 2.

Fig. 5 is a sectional elevation of another form of hasp.

Fig. 6 is a back view of a lock to be used with the hasp Fig. 5.

Fig. 7 is an elevation of a further form of hasp.

Fig. 8 is an end view of Fig. 7.

Fig. 9 is a back view of a lock to be used with the hasp Figs. 7 and 8.

Fig. 10 is a section of Fig. 9.

Fig. 11 is a front view of another form of hasp.

Fig. 12 is an end view of Fig. 11.

Fig. 13 is a front elevation of a lock to be used with the hasp Figs. 11 and 12.

Fig. 14 is a view of Fig. 13 with the front part of the casing removed.

Fig. 15 is a back view of a still further form of hasp.

Fig. 16 is a side view of Fig. 15.

Fig. 17 is a view of the lock to be used with the hasp Figs. 15 and 16.

Fig. 18 is a section of Fig. 17 on the dotted lines A—B.

Where permissible the same letters of reference are used in all the figures of the drawings.

With reference to Figs. 1—4, *a* is the hasp to be fixed to the hinged lid of the attaché case, and *c* is the lock to be fixed to the body of said case.

The hasp comprises an attachment plate *a*2, provided with a lug *a*3 with which the pivoted catches, hereinafter described, engage.

The lock *c* has a casing provided by a back plate *c*2, a front box *c*3 open at top *c*4 and closed at sides *c*5, *c*5, and bottom *c*6. A knob *d* is fixed to the face of the front box *c*3 by clinchings at *d*2. A ring *e* is mounted upon this knob to revolve against the face of the front box, having a handle *e*2 to grip it, and being provided with a stud *e*3 which projects through an arcuate slot *e*4 in the face of said front box *c*3 into the interior of the casing.

A slidable member *f* is fitted within the front box *c*3 to lie between said box and the back plate *c*2. This member has rigid sides *f*2, *f*3, and a rigid upper wall *f*4, being open at its back, and formed at *f*5 with a straight crossing slot to be engaged by the stud *e*3 on the ring *e*.

Two catches *g* and *h* are pivoted to the top of the slidable member *f* by the two pivoting pegs *g*2, *h*2, each being fitted with a torsional spring *i* to normally swing it outwardly, as shown in Fig. 4 when clear of the sides of the front box *c*3. Said slide also carries a rigid peg *j* upon which a torsional spring *j*2 is mounted for its one limb *j*3 to operate against the side of the slide, and its other limb *j*4 against the stud *e*3. Said slidable member *f* is moved vertically in the front box by the ring *e*, the spring *i*2, and by the hasp *a*, as will be hereinafter described, guided during its movement by the sides of said front box.

k is a notched gap in the slidable member *f*, and *k*2 indicates a slidable locking bolt adapted to be operated by a key working on the key peg *k*3. In locking position, the stump *k*4 of the slide bolt *k*2 engages the side notch of the gap *k* for key locking the slidable member with its catches *g*, *h* in engagement with the hasp, and in unlocking position, as shown in Fig. 2, the stump is free of the gap so that the slidable member can move. The key peg *k*3 and the slide bolt *k*2 are shown in dotted lines in Fig. 2, because these elements are mounted on the back plate *c*2 which is removed in this figure.

The drawings show that the stud *e*3 is carried by the ring *e*; that the arcuate slot *e*4 is formed in the face of the front box *c*3; that the straight

crossing slot f_5 is formed in the slidable member f ; and that the pivoted catches g, h , and the torsional spring j_2 are carried by said slidable member, and that this slidable member also carries the rigid upper wall f_4 which constitutes a push wall.

Now assuming the hasp Fig. 3 is put into engagement with the lock Fig. 4, the catches g and h being open, the lug a_3 presses against the rigid upper wall f_4 of the slidable member to force said slidable member downwardly. This causes the ring e to be partly revolved and the catches g, h , to gradually close in by pressure of their backs against the side walls of the front box c_3 , so that said catches gradually swing over the lug a_3 to automatically secure the hasp to the lock, the movement being aided and completed by the torsional spring j_2 .

To disengage the hasp from the lock the ring e is hand moved from its position Fig. 2 to its position Fig. 4. This action positively lifts the slidable member f together with the hasp and the catches until said catches are clear of the sides c_5, c_5 , of the front box, when said catches automatically swing clear of the lug a_3 , enabling the hasp a to be entirely removed by wholly lifting the hinged lid to which it is attached; it being clear that during the first movement the disengagement of the hasp from the lock has been started by positive pressure of the rigid upper wall f_4 against the underside of the lug a_3 , with the result that the lid is partially opened during the release of the hasp.

In Figs. 5 and 6, the catches g and h are carried by the slidable member f , but a fixed stud l is provided upon the front box c_3 to automatically swing the catches outwardly when the slidable member f is lifted, an inclined edge l_2 on each of the catches co-operating against the sides c_5, c_5 , of the front box to close inwardly the catches when pressure is applied against the upper ends thereof by the lug a_3 , a part of which lug is constituted by a stud m around which the catches close for fastening the hasp to the lock.

In Figs. 7-10 a single pivoted catch g is provided to close onto the lug a_3 of the hasp a , this catch being carried by a slidable member f and having a torsional spring i to normally swing it outwardly.

With reference to Figs. 11-14 two pivoted catches g and h are provided upon the back plate c_2 of the lock casing, to be wholly located within the casing, the lug a_3 of the hasp a entering said casing at the edge opening n , and operating against the parts o of the catches to automatically rock the latter for their engagement with the lug, the completion of the engagement being through the limb spring q also disposed within the casing, this spring completing each movement of the catches, and holding them in such positions. The two catches g, h , are moved to release the lug a_3 of the hasp by hand operation towards each other of the two slidable fingers grips r and s applied to the face of the front box c_3 , these two finger grips connecting with the two catches at r_2, s_2 . In this form of the invention, as also in all the forms of the invention previously described, there is still the positive start of the disengagement of the hasp from the lock from hand operation of the catches to release, and also the positive start of the en-

gagement through downward pressure of the hasp lug a_3 .

With reference to Figs. 15-18, a hasp a of the known hinged kind carries upon it a rigid loop a_4 (corresponding to the lug a_3). The lock c has a front opening t for the loop to pass through into the lock casing, and the latter is provided with a single pivoted catch g formed with an inclined nose g_3 to engage the loop and with an inclined push-out abutment g_4 to contact the exterior of the loop, a spring q completing the movement of the catch in its two directions. If the loop a_4 is pushed through the opening t from the front of the casing, as would be the case in closing the hasp, the back of the loop a_4 presses against the inclined abutment g_4 , and thereby rocks the catch so that its inclined nose g_3 will be moved into engagement with the loop, and so secure the hasp to the lock, the ring e being moved at the same time by the catch. If now the ring e is revolved by hand to actuate the catch g the nose g_3 will be first removed from the loop, and then the inclined abutment g_4 will operate against the back of the loop to start the positive disengagement of the hasp from the lock.

Having now described my invention, what I claim and desire to secure by Letters Patent is:

1. A fastening of the kind described, comprising a rigid hasp, a lug carried by the hasp, a lock casing having an open side to receive the lug, a slidable member guided in said casing and being disposed with one edge thereof adjacent said open side to be displaced by the lug entering the casing, a pivoted catch carried on said slidable member adjacent the open side of said casing to be swung into engagement with said lug when said slidable member is inwardly displaced, means for holding said catch out of engagement with said lug while said slidable member is in its outermost position, hand-operated means projecting to the exterior of said casing for moving said slidable member from its innermost to its outermost position, and a spring within said casing to normally hold said slidable member in its innermost position when said catch engages said lug.

2. A fastening, as claimed in claim 1, in which said hand-operated means includes a revoluble element on the exterior of the casing, and a stud fixed on said revoluble element and projecting through an arcuate slot in the casing into a transverse slot provided in said slidable member.

3. A fastening, as claimed in claim 1, in which said hand-operated means includes a revoluble element on the exterior of the casing, and a stud fixed on said revoluble element and projecting through an arcuate slot in the casing into a transverse slot provided in said slidable member, said spring cooperating with said stud to hold it normally in a position in which said slidable member is withdrawn from the open side of said casing.

4. A fastening, as claimed in claim 1, in which a second catch is pivoted to said slidable member, adjacent the open side of said casing to be swung into engagement with said lug in a direction opposite to that of said first catch, when said slidable member is inwardly displaced.

CHARLES WILLIAM CHENEY.
